UNITED STATES PATENT OFFICE

HAVILAND H. PLATT, OF WALLINGFORD, PENNSYLVANIA

SAIL

Application filed August 27, 1928. Serial No. 302,223.

This invention relates to improvements in wind propelled boats, and relates more particularly to improvements in the sails constituting an essential part thereof.

5 The principal object of the invention is to provide a sail of novel form which shall be generally more efficient than the sails of the prior practice.

The invention also resides in certain novel 10 and advantageous structural features herein-after set forth and illustrated in the attached drawings, in which:

Figure 1 is a side elevational view of a boat equipped with a sail made in accordance with 15 my invention;

Fig. 2 is a front elevational view of the boat;

Fig. 3 is a transverse section on the line 3—3, Fig. 1, and

20 Fig. 4 is a diagram illustrating the operating characteristics.

With reference to the drawings, the sail 1 in a preferred form consists of a hollow framework which in side elevation may conform proportionally to any of the accepted sail shapes and which in horizontal cross section takes the form of an efficient airfoil section, such for example as that known as Göttingen 410. This horizontal sectional form 25 preferably is maintained consistently from top to bottom of the sail. This framework is covered with sail cloth or other suitable material which constitutes the effective sail surface and which preferably is drawn tightly 30 over the framework so that it conforms closely to the outline of the latter.

In one embodiment of this sail, the framework may consist of a plurality of substantially flat frames 2, see Fig. 3, corresponding 40 in form, for example, to the said airfoil section, these frames being individually braced and struttured in any desired and practical manner and varying as to length in accordance with the general form of sail desired. 45 These frames in assembly are arranged in superimposed relation, and each is connected with the adjacent frame or frames by flexible means of such length that when the framework is extended a sail of desired surface area 50 is obtained. Obviously, the covering material

itself may constitute the flexible connecting means. The sail so constructed is collapsible vertically, the individual horizontal frame pieces collapsing one upon the other as the sail is released from the top. This permits reefing of the sail in the usual manner. 55

As shown, a passage 3 is provided through the frames for the mast 4, which thus extends through the interior of the sail and is entirely surrounded and embraced thereby except in those portions which project at the top and bottom of the frame structure. The mast should be located in advance of or closer to the leading edge of the sail than the center of pressure which, in the particular airfoil section Göttingen 410 lies from the leading edge a distance equal approximately to 25% of the length of the foil. 60

The flat frames 2 which make up the framework as a whole are so relatively arranged as to preserve the predetermined relation between mast position and center of pressure. The sail may be elevated and lowered on the mast by means of the usual tackle attached to the mast and to the top of the sail structure. Preferably the lowermost frame of the structure is made sufficiently heavy to function as a boom. 65

A sail constructed on the principle outlined above has certain material advantages 70 over the forms of sail now commonly employed. The aerodynamic efficiency of my sail is considerably greater than that of sails of the usual form, which for any given sail area gives an increased propulsive force and affords better speed sailing into the wind. 75 A sail constructed in accordance with my invention also possesses the characteristic of developing maximum efficiency at a relatively low angle of attack, which permits sailing closer into the wind. My sail also reduces the capsizing force of the wind, permitting a larger sail area or greater safety with a given area than can be obtained with sails of the usual design. The general efficiency is also 80 increased, in that the sail substantially encloses and thereby eliminates the air resistance of the mast. 85

Figure 4 presents a diagram affording a 90 graphic comparison of the action of the or- 95

inary sail with a sail made in accordance with my invention. Assuming a lift force of the value shown, it will be apparent that the drag force for my sail (designated by line D) will be less than the drag (D') for a sail of the usual form, the relative lengths of D and D' as shown being approximately proportionate to the actual values taken from wind tunnel data. Combining the forces for the respective sails gives for my sail an effective propulsive component P, and for the other sail a very considerably small component P'. The advantage of the new sail will be apparent.

15 I claim:

1. In a sail boat, a mast, and a substantially rigid sail of symmetrical section substantially surrounding said mast.
2. In a sail boat, a mast, and a sail substantially surrounding said mast, said sail being of symmetrical section and conforming throughout its horizontal cross section to an airfoil section of predetermined efficiency.
3. A sail comprising a plurality of flat symmetrical frames each having throughout substantially the airline of an airfoil section and connected in spaced relation vertically, and a fabric cover for the framework formed by said sections, said framework being of sufficient width to permit the passage through the interior of a mast upon which the sail may be supported.
4. A sail comprising a hollow structure of symmetrical section and conforming throughout its cross sectional form substantially to an airfoil section.
5. A hollow sail comprising a supporting frame of symmetrical section, and a cover therefor, said frame being adapted to maintain the cover throughout the horizontal section in the form of an efficient airfoil section.
6. In a boat, a mast, and a sail completely surrounding the mast, said sail being of symmetrical section and being held transversely and with substantial rigidity in the form of an efficient airfoil section.

HAVILAND H. PLATT.
